(57) **CLAIM**

The ornamental design for a thin client, as shown and described.

DESCRIPTION

FIG. 1 is a perspective view of the thin client showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing of the various elements including the data storage device, input/output ports, buttons, and indicating light are for the purpose of illustrating unclaimed portions and form no part of the claimed design.

1 Claim, 7 Drawing Sheets
